HOLLIS H. HARRIS, OF LORAIN, OHIO, ASSIGNOR TO THE THEW AUTOMATIC SHOVEL COMPANY, OF LORAIN, OHIO, A CORPORATION OF OHIO.

EXCAVATING MECHANISM.

1,289,166.

Specification of Letters Patent. Patented Dec. 31, 1918.

Application filed February 15, 1918. Serial No. 217,442.

To all whom it may concern:

Be it known that I, HOLLIS H. HARRIS, a citizen of the United States, residing at Lorain, in the county of Lorain and State of Ohio, have invented a certain new and useful Improvement in Excavating Mechanism, of which the following is a full, clear, and exact description, reference being had to the accompanying drawings.

This invention relates to power shovels or other excavating mechanism adapted to be propelled and provided with a supporting truck with a superstructure adapted to swing thereon. The object of the invention is to provide efficient means for steering the machine. This is accomplished by swiveling one of the axles at its center, and swinging the axle either automatically, consequent upon the swinging of the superstructure, or by hand independently of such swinging. The invention is hereinafter more fully described and the advantages of the mechanism illustrated explained, and the essential characteristics are summarized in the claims.

In the drawings, Figure 1 is a side elevation of a portion of a steam shovel equipped with my automatic and hand steering mechanisms; Fig. 2 is a plan partly broken away of the structure shown in Fig. 1; Fig. 3 is a diagrammatic plan illustrating the swinging of the swiveled axle by swinging the superstructure; Fig. 4 is a side elevation and Fig. 5 a plan of that portion of the automatic steering mechanism which is adapted to be connected with the outer end of the swiveled axle. The remaining figures illustrate the hand steering mechanism, Fig. 6 being a detached plan thereof, Fig. 7 a detail illustrating the connection of the link with the bell-crank, Fig. 8 a longitudinal section through the clevis connected with the bell crank, and Fig. 9 an enlarged longitudinal cross section through the frame of the truck.

As shown in Figs. 1, 2 and 3, 10 designates the body of a truck, 11 wheels journaled on stationary axles carried by the truck, 12 an axle swiveled at its center (16) to the truck and 13 wheels on the swiveled axle. 20 designates a superstructure having a platform swiveled at 21 to the truck and adapted to carry suitable excavating mechanism, as a boom, cables, etc. These latter parts are not shown, except that Fig. 1 illustrates at 23

the pivotal anchorage for the lower end of the boom.

The truck is shown as provided with a stationary horizontal gear 15 concentric of the axis 21. With this gear meshes a pinion 25 carried on a vertical shaft depending from the platform and adapted to be rotated by suitable mechanism (not shown) which may be carried by the platform. The rotation of the pinion 25 will swing the entire superstructure about the axis 21 one way or the other according to the direction of rotation.

To enable the swinging of the superstructure to swing the swiveled axle 12 to steer the machine, I provide a link mechanism connecting the superstructure platform with the end of the swiveled axle. This will now be described.

The swiveled axle extends beyond the outer face of one of the wheels 13. Journaled on it at this point is a block 30 shown as retained in place by a washer 31 held by a cap-screw 32 screwing into the end of the axle. A link 40 is pivoted to this block on a vertical axis. As shown most clearly in Figs. 1 and 4, this link is bifurcated near its end and has its two arms 41 and 42 extending respectively above and below the block 30. A suitable pin 45 extends through the arms 41 and 42 and the intermediate block 30, whereby the link is pivotally connected to the axle on a vertical pivot. This together with the horizontal journaling of the block 30 on the swiveled axle makes a universal joint between the link and axle.

At its other end the link 40 is universally jointed to the platform. To effect this, I provide a bracket 50 secured to one of the sills 27 of the platform. This bracket has a vertical ear or web portion 51 in which is swiveled on a horizontal axis a clevis 52 which is pivoted on a vertical axis to the link 40. The clevis is a U-shaped member extending above and below the link 40 and pivoted to it by a vertical pin 54 extending through the arms of the clevis and an eye in the interposed link. The clevis has a central shank 55 which extends through the ear 51 and thereby swivels the clevis to the bracket 50. A suitable nut 56 on the shank mentioned holds the clevis to the bracket,

With such a construction as described, the swinging of the superstructure 20 causes the link 40 to either pull or push on the end of the swiveled axle 12 and thereby turn such axle to shift the wheels 13 relative to the truck and thus steer the machine. The pivotal point 54 for the upper end of the link is nearer the longitudinal center of the truck than the outer side of the wheel 13. Accordingly, the link 40 is bent at a distance from its lower end approximately equal to the radius of the wheel, the point of bending being indicated at 48. This enables the forked portion of the link to normally lie parallel with the outer face of the wheel 30 and comparatively close to it while the upper end is closer to the truck frame, as shown clearly in Fig. 2.

The link 40 is of such length and its driving end so located that the link swings away from the wheel 13, for either direction of swinging of the platform, so that there can be no binding on the wheel. This is illustrated in Fig. 3, where the normal position of the steered wheel, the link and its driving pivot is shown by the broken lines 13^a, 40^a and 54^a. The platform swings about the axis 21 and the swiveled axle about the axis 16. Now, if the platform be turned toward the side where the link is located the pivot pin 54^a swings in the arc A concentric of the axis 21 into the position shown at 54 in full lines in Fig. 3. This necessarily displaces the link 40 longitudinally, causing the universally connected lower end of it to swing in an arc about the center 16. In such swinging the outward travel of the pivot 54 is more than the outward travel of the corner of the wheel 13, with the result that the portion 48 of the link adjacent to the wheel corner swings slightly away from the wheel. The slight divergence, shown in Fig. 3, is increased as the platform swings farther in that direction.

Now, if the platform should swing in the opposite direction from the normal position shown in Fig. 2, the corner of the wheel 13 swings inwardly faster than the head end 50 of the link 40 is swung along the arc A so that the corner of the wheel travels relatively away from the link 40. This is illustrated by broken lines in Fig. 3 where the pivot pin 54 is shown positioned at 54^b, the wheel 13 in the position 13^b, and the link 40 in the position 40^b. It will accordingly be seen that whichever way the superstructure swings the link 40 clears the wheel 13.

In the ordinary use of the shovel it is desired to have the truck stand stationary or be propelled in a straight line and the superstructure swing freely on its axis. This is allowed by disconnecting the link 40 from the swiveled axle. The disconnection is easily effected by withdrawing the pin 45,

freeing the bifurcated end of the link from the block 30.

To conveniently support the link 40 when it is disconnected from the swiveled axle, I provide a hook 60 secured to the superstructure frame and facing outwardly, as shown in Figs. 1 and 2, the support for the hook being omitted in Fig. 2. When the link is disconnected it may be simply raised and swung inward and deposited in the loop 75 of the hook 60. The pivot pin 45 is ordinarily replaced in the forks 41 and 42 as soon as removed from the block and the link then swung up and supported by the hook, where it may be carried indefinitely out of the way.

To enable the swiveled axle to be turned whenever desired by hand independently of the superstructure, I provide a very simple and effective mechanism, which may be connected whenever desired, and which is illustrated in Figs. 1, 2 and 6 to 9 inclusive. This mechanism consists of a screw 70, threaded in a nut 71 swiveled to the truck frame; a clevis 72 in which the inner end 90 of the shaft of the screw is rotatably mounted; a bell-crank 73 connected to the clevis and pivoted to the frame at 74 and having an arm 75; and a movable link 76 adapted to connect the arm 75 with an eye 77 secured to the swiveled axle 12.

With such a structure as just described the rotation of the screw 70 (as for instance by a hand crank 80 removably connected to the squared end of the screw), will result in the 100 swinging of the crank-bell one way or the other and the pulling or pushing on the link 76, to swing the swiveled axle accordingly.

The attachment of the nut 71 and bell-crank 73 to the truck frame will, of course, vary with different forms of frame. I have shown a frame in which there are longitudinal I-beams 17 and transverse I-beams, of which two are shown at 18 and 19. It is convenient to swivel the nut 71 to one of the lower flanges of the I-beam 18 as indicated at 82 in Figs. 1 and 9. Similarly the pivot of the bell-crank may be connected to one of the lower flanges of the transverse I-beams 19. Thus Fig. 9 shows the stud 74, 115 forming the journal for the bell-crank, extending through a lower flange of the I-beam 19.

To prevent the hand steering device from interfering with the automatic steering, I 120 make the link 76 readily disconnectible. This link is preferably a horizontal bar having down-turned ends 78 and 79, Fig. 1. The down-turned end 78 extends through the eye in the outer end of the bell-crank arm 75, 125

To enable the link 76 to be conveniently hooked into the arm, I form a groove 85 extending across the upper face of the arm, and I locate the hole 86, which the point 79 is intended to occupy, at the mid point of 130

this groove. Now, in putting the link in place, the end 78 is readily hooked into the eye 77 and the end 79 brought approximately into its engaging position. If, now, 5 the bell crank is approximately in position for entrance of the hook, the point 79 may be readily placed in the groove 85 by feeling. Then the bell crank is swung one direction or the other to bring the hole 86 into registration with the point 79 and the link will 10 drop into place. This enabled the link to be placed without visual observation, which is considerably advantageous, owing to the position of the mechanism.

15 Having thus described my invention, what I claim is:

1. The combination of a truck having a swiveled axle, a superstructure swiveled on the truck, and a link, one end of which is 20 pivotally mounted on the superstructure approximately at the side of the swivel and the other end pivotally mounted on the swiveled axle.

2. The combination of a truck having a 25 swiveled axle, a platform swiveled to the truck, a link connected at one end by a universal joint to a part rigid with the platform and at the other end by a universal joint with the swiveled axle.

30 3. The combination of a truck having a swiveled axle, a superstructure swiveled to the truck, a link connected at one end to the outer end of the swiveled axle beyond the wheel, and means pivotally connecting the other end of the link to the superstructure.

35 4. The combination of a truck having a swiveled axle with wheels thereon, a platform swiveled to the truck on a vertical axis, 40 a bracket at one side of the platform, a link pivoted at one end to the bracket and extending on the outer side of the wheel and pivotally connected with the axle.

45 5. The combination of a truck having a swiveled axle with wheels on it, a platform swiveled to the truck on a vertical axis, a bracket carried by the platform, a clevis swiveled to the bracket, a link pivoted to the clevis, a block mounted on the axle outside

of the wheel, and a pivotal connection between said block and the adjacent end of the link.

6. The combination of a truck having a swiveled axle carrying wheels, a platform swiveled to the truck, a link connected to the platform, said link being provided with a fork on the outer side of one of the wheels mentioned, a block mounted on the swiveled axle beyond the wheel, said fork extending onto the upper and lower faces of the block, 60 and a removable pin pivotally connecting the fork to the block.

7. The combination of a truck having a swiveled axle carrying wheels, a platform mounted on the truck to turn on a vertical 65 axis, a link universally connected at one end with the platform, disconnectible means connecting the other end of the link with the swiveled axle, and means carried by the platform for supporting the link when disconnected.

8. The combination of a truck having a swiveled axle carrying wheels, a platform mounted on the truck to turn on a vertical 75 axis, a link movably connected at one end with the platform, disconnectible means connecting the other end of the link with the swiveled axle, and a hook carried by the platform and adapted to receive and support the link adjacent to its free end when 80 the link is swung up into approximate parallelism with the platform.

9. The combination of a truck having a swiveled axle carrying wheels, a platform mounted on the truck to turn on a vertical 85 axis, a link movably connected at one end with the platform and bifurcated at the other, a block on the swiveled axle adapted to be engaged by such fork, a removable pin connecting the fork with the block, and a 90 hook carried by the platform and adapted to receive and support the link adjacent to its forked end when the link is swung up into approximate parallelism with the platform.

In testimony whereof, I hereunto affix my 95 signature.

HOLLIS H. HARRIS.
